UNITED STATES PATENT OFFICE.

WILLIAM A. BRYANT, OF NEWARK, NEW JERSEY.

DESIGN FOR A FINGER-RING.

SPECIFICATION forming part of Design No. 17,906, dated November 29, 1887.

Application filed September 17, 1887. Serial No. 250,010. Term of patent 7 years.

To all whom it may concern:

Be it known that I, WILLIAM A. BRYANT, of Newark, in the county of Essex and State of New Jersey, have originated and produced 5 a new Design for Finger-Rings, of which the following is a specification.

My design is specially intended for finger-rings made for children.

The design consists in a finger-ring having 10 outwardly-projecting flange-like portions adjacent to the edges between the latter, a band-like portion bearing the letters of the alphabet, and grooves between the band-like portion and the flange-like portions.

15 The accompanying drawings illustrate a ring embodying my design.

Figure 1 is an edge view of the ring. Fig. 2 is a side view of the ring. Fig. 3 is a transverse section of the ring.

20 Similar letters of reference designate corresponding parts in all the figures.

In the ring which I have represented there are outwardly-projecting flange-like portions a' a'' adjacent to the edges. Midway between

these portions is a band-like portion, a^3 , on 25 the exterior of the ring. Between the band-like portion a^3 and the outwardly-projecting flange-like portions a' a'' grooves a^4 a^5 are formed.

The letters of the alphabet are shown as raised upon and projecting from the band-like 30 portion a^3 .

Between the letters A and Z, I have shown a raised panel, a^6 , upon the band-like portion a^3 .

What I claim as my design, and desire to 35 secure by Letters Patent, is—

The design for a finger-ring, comprising outwardly-projecting flange-like portions adjacent to the edges of the ring, between the latter a band-like portion bearing the letters of 40 the alphabet, and grooves between the band-like portion and the flange-like portions, substantially as shown and described.

WM. A. BRYANT.
